UNITED STATES PATENT OFFICE.

WILLIAM SMITH, OF PHILADELPHIA, PENNSYLVANIA.

DESIGN FOR A FRINGE OR TASSEL BLOCK.

SPECIFICATION forming part of Design No. 15,726, dated January 13, 1885.

Application filed December 1, 1884. Term of patent 14 years.

To all whom it may concern:

Be it known that I, WILLIAM SMITH, a citizen of the United States, and a resident of Philadelphia, Pennsylvania, have invented a new and Original Design for an Upholstery Fringe or Tassel Block, of which the following is a specification.

My design is fully shown in the accompanying drawings, in which Figs. 1, 2, 3, and 4 are side views of different forms of block embodying the design; Figs. 5, 6, 7, and 8, diagrams illustrating the cross-sectional shape on the line $x-x$ of the blocks, Figs. 1, 2, 3, and 4, respectively; and Figs. 9, 10, 11, and 12, similar diagrams showing the shape of the blocks on the line $y-y$.

The design consists of a block having a series of rows of circular or oval facets, the number of which varies in accordance with the size and shape of the block. Thus in Figs. 1, 5, and 9 I have shown a block substantially square in cross section, and having central facets, a , upper facets, b , and lower facets, d , and in Figs. 2, 6, and 10 I have shown a hex-

agonal block having three rows of facets, and in Figs. 3, 7, and 11 an octagonal block likewise cut, while in Figs. 4, 8, and 12 is shown a hexagonal block having two rows of facets, b and d . The circular or oval shape of the facets is, however, preserved in all of the forms of block shown.

I claim—

1. The design for a fringe or tassel block, said design consisting of the block having a series of rows of circular or oval facets, as shown and described.
2. The design for a fringe or tassel block, said design consisting of the block having a central row, a , and upper and lower rows, b and d , of circular or oval facets, as shown and described.

In testimony whereof I have signed my name to this specification in the presence of two subscribing witnesses.

WM. SMITH.
